UNITED STATES PATENT OFFICE.

CHARLES GIRO McKENDRICK, OF MONROE, NEW YORK.

AIR-MOISTENER.

No. 914,863.

Specification of Letters Patent. Patented March 9, 1909.

Application filed February 26, 1908. Serial No. 417,847.

To all whom it may concern:

Be it known that I, CHARLES GIRO McKENDRICK, a citizen of the United States, and a resident of Monroe, in the county of 5 Orange and State of New York, have invented a new and Improved Air-Moistener, of which the following is a full, clear, and exact description.

The invention relates to steam radiators, 10 and its object is to provide a new and improved moistener for moistening the air in the room in which the radiator is located, the moistener being connected with the steam chamber of the radiator and arranged 15 to allow steam to pass into the moistener and to be diffused by the same into the surrounding air, to moisten the same.

The invention consists of novel features and parts and combinations of the same, 20 which will be more fully described herein-after and then pointed out in the claims.

A practical embodiment of the invention is represented in the accompanying drawings, forming a part of this specification, 25 in which similar characters of reference indicate corresponding parts in both views.

Figure 1 is a perspective view of the improvement as applied; and Fig. 2 is an enlarged sectional side elevation of the improvement. 30

A pipe A is attached to the steam radiator B to connect with the steam chamber, and the outer end of the pipe A is provided with a valve C and terminates in a pipe D, preferably disposed vertically, and closed at the top by a cap E or other suitable means, said pipe being provided with series of perforations, as shown in Fig. 2.

An absorbent or permeable material F is 40 wrapped around the perforated pipe D, so that the steam can pass from the steam chamber of the radiator B by way of the pipe A, and the perforations in the pipe D, into the said absorbent material, to be 45 gently diffused by the latter into the room in which the radiator B is located. In practice, I prefer to wrap the inner portion F¹ of the absorbent or permeable material F tightly, and the outer portion F² loosely 50 as shown in Fig. 2, and inclose the whole within a shell G of wire gauze, perforated sheet metal or the like, to securely hold it in position against unwrapping. A drip

cup H is preferably arranged on the lower end of the pipe D directly below the lower 55 end of the steam absorber, so that any water of condensation that may drip off the absorber falls into the drip cup H and is evaporated therein by the heat radiating from the steam radiator B. The amount of 60 steam allowed to pass from the steam compartment of the radiator B into the absorber can be conveniently regulated by the operator manipulating the valve C accordingly.

By the arrangement described, a desired 65 amount of moisture is given off to the air in the room in which the radiator B is located, the moisture being supplied by the radiator B.

By arranging the absorbent material in 70 the manner described, the device is rendered completely noiseless, and by its simple construction can be cheaply manufactured and readily applied to radiators now in use.

Having thus described my invention, I 75 claim as new and desire to secure by Letters Patent:

1. As a new article of manufacture, an air moistener, comprising a perforated pipe having a closed upper end and adapted to be 80 attached to a radiator in a vertical position, permeable material in sheet form surrounding the perforated portion of the pipe, a foraminous cylinder surrounding the permeable material, and a drip cup on the lower 85 end of the pipe below the permeable material and its inclosing cylinder.

2. An air moistener, consisting of a perforated pipe adapted to communicate with the steam space of a radiator, and to be held 90 in a vertical position, a closure for the upper end of the pipe, sheets of permeable material surrounding the perforated part of said pipe, a foraminous cylinder surrounding the sheets of permeable material, a valve in the 95 lower end of the said pipe, and a drip cup surrounding said pipe intermediate of the valve and the perforated portion of the pipe.

In testimony whereof I have signed my name to this specification in the presence of 100 two subscribing witnesses.

CHARLES GIRO McKENDRICK.
